ATTACHMENT FOR MINING MACHINES

William Archibald Logan, Kinghorn, Fife,
ScotlandApplication April 2, 1935, Serial No. 14,198
In Great Britain April 6, 1934

2 Claims. (Cl. 262—30)

The subject of my invention is an attachment for longwall mining machines.

An attachment according to the invention includes a cutter element adapted to make a horizontally disposed incision in the mine seam above the incision made by the cutter element of the mining machine, a shearing cutter element adapted to make an upright incision in the seam between the inner ends of the aforesaid incisions, means for loading the mined material on to a face conveyor or the like, haulage means for imparting feeding movement to the mining machine and the attachment, means for removing cuttings from the cutter element of the mining machine, and a motor and speed-reducing gearing for driving the said components of the attachment.

The attachment is readily convertible for operation on a mine seam disposed on either side of the line of travel of the mining machine.

In the accompanying drawings Fig. 1 is a plan view, Fig. 2 a side elevation, and Fig. 3 an end elevation, showing an attachment according to the invention attached to the gear head of a longwall mining machine. Figs. 4 and 5 are fragmentary diagrammatic detail views of parts of the attachment. Fig. 6 is a transverse section of a mine seam showing the incisions made in said seam by the cutter elements of the mining machine and attachment.

Referring to the drawings, 1 denotes the horizontally disposed cutter jib, 2 the cutter chain, and 3 the gear head, of a longwall mining machine.

Attached to the gear head 3 is an attachment 35 including adjoining steel casings 4 and 5, respectively. The casing 4 houses reduction gearing hereinafter described, and the casing 5 houses an electric motor the rotor 6 of which is rotatable on a vertical axis.

A reduction gear train 7—10 (Fig. 4) partly housed within the casing 4, operatively interconnects the rotor shaft of the motor with a hollow vertical shaft 11 journalled within the casing 4 and telescopically engaged by a second vertical shaft 12 journalled and axially located in a rotatable turret 13 fitted on top of the casing 4. On the upper end of the shaft 12, which projects upwardly through the turret 13, is secured a sprocket wheel 14 which drives a cutter chain 15 circulating around a horizontally disposed jib 16 attached by a bracket 17 to the turret 13. The cutter chains 2 and 15 circulate in opposite directions as indicated by arrows in Fig. 1. The turret 13, which carries the cutter jib 16 and its cutter-chain-driving shaft 12, is mounted for

vertical adjustment on the casing 4, adjustment being effected by the operation of turret-supporting screws 18.

As is understood, the cutter jib 1 is adapted to be swung in a horizontal plane through a semi-circle so that it may be positioned for operation at either side of the mining machine. The cutter jib 16 is also swingable for operation at either side of the attachment, there being associated with the turret 13, for this purpose, a rope sheave 19 around which a rope may be trained for the purpose of slewing the cutter jib 16 as required. Cutter-jib-locking means of usual design may be provided for locking the cutter jibs in operative position.

Surrounding the upper end of the stator 6^a of the motor is a rope haulage drum 20 adapted to be stepwise rotated by a hydraulic reciprocating motor indicated conventionally at 21 (Fig. 5) and operatively connected to a scroll cam 22 secured on a shaft 23 (Fig. 4) carrying a gear pinion 24 which meshes with a gear ring 25 unitary with the drum 20. The hydraulic motor 21 imparts vibratory motion to a lever 26 in opposition to the action of a spring 27, whereby to impart stepwise rotation to the scroll cam 22 through the medium of rollers or balls 28 co-operating with wedging surfaces 29 presented by the scroll cam 22. Adjustable means is provided at 30 in the operative connection between the hydraulic motor 21 and the lever 26, whereby to permit variation of the stepwise movement transmitted to the drum 20. Pressure oil is supplied to the hydraulic motor 21 by a pump 31 (Fig. 4) driven by means of an eccentric 32 from a shaft 33.

The shaft 33 extends transversely of the casing 5 and is driven from the rotor 6 of the electric motor through a gear train including the rotor pinion 7, an idler gear wheel 34, a gear wheel 35, and a worm gear 36 meshing with a worm wheel 37 on the shaft 33.

The attachment is provided with a hollow base 38 within which circulates a scraper conveyor including a chain 39 equipped with scrapers 40 adapted to remove the cuttings from the cutter chain 2 and to discharge said cuttings through an opening 41 at the rear end of the hollow base 38. The chain 39 is trained around a pair of sprockets 42 within the front end of the base 38 and around a second pair of sprockets 43 within the rear end of the base 38. The scraper conveyor is driven from the shaft 11 through gear pinions 44, 45 which transmit the drive to one of the chain sprockets 42. A channel-shaped

soleplate 46 forms the bottom wall of the cavity housing the scraper conveyor 39, 40.

47 denotes generally a loader conveyor which is bolted to a box-base 48 unitary with a turn-table 49 incorporated in the rear part of the casing 5 and partially rotatable about a vertical axis to permit the box-base 48 to be swung from one side to the other side of the attachment. The loader conveyor proper comprises three spaced chains 50 carrying transversely disposed scrapers 51 and wrapping sprockets on a spaced pair of shafts 52, 53 of which the shaft 53 is driven from the shaft 33 through a sprocket 54, a chain 55, and a sprocket 56. Attached to the front of the box-base 48 is a wedge-shoe 57 extending in advance of the loader conveyor. Journalled immediately in front of the loader conveyor is a peripherally spiked roller 58 adapted to prevent the shoe 57 from jamming in the cut made in the mine seam by the cutter chain 2 and to assist in lifting the mined material on to the loader conveyor 47. The inner end of the roller 58 is geared to the shaft 33 through chain sprockets 59, 60 and a chain 61. 62 denotes a shearing cutter chain which is driven from the roller 58 through chain sprockets 63, 64 wrapped by a chain 65.

The cutter chain 62 circulates around a jib 66 which is supported from the wedge-shoe 57 by a bracket 67.

Rollers 68 journalled in front of the roller 58 serve to assist the mined material to slide on to the wedge-shoe 57, so that the material will be entrained by the spikes on the roller 58.

69 denotes a roller journalled in the box-base 48 behind the loader conveyor and adapted to receive the return bight of a face conveyor belt 70.

For securing the attachment to the gear head 3 of the mining machine the attachment is provided with a pair of tram-like extensions 71 adapted to be bolted to the gear head 3.

The partially rotatable box-base 48 permits the loader conveyor 47 to be assembled at either side of the attachment, the shearing cutter jib 66 being mountable, for this purpose, on either side of the loader conveyor 47, and the cutter chain 62 being operatively connectible to either end

of the roller 58. The chain sprockets 56, 59 may be coupled to either end of the shaft 33.

In operation, prior to fixing the attachment to the mining machine, the cutter jib 1 of the machine is swung under the mine seam and locked in cutting position, and a space of about ten feet is cut from the seam and the mined material filled out. The attachment is then moved under its own power into position against the gear head 3 of the machine and bolted thereto. The face conveyor belt 70 is trained round the roller 69 at the rear of the loader conveyor. As will be understood, as the machine and the attachment are fed forwardly by means of the haulage drum 20, the seam is horizontally undercut, sawn horizontally on top, and sheared vertically at the back, by the cutter chains 2, 15 and 62, respectively, as shown at 2^a, 15^a and 62^a, respectively, in Fig. 6, the mined material being caught up by the loader conveyor 47 and transferred rearwardly on to the face conveyor 70.

The motor of the attachment may be stopped and started by the main switch of the mining machine, or may be operated independently.

I claim:—

1. For a longwall mining machine having a horizontally disposed cutter element and a face conveyor, an attachment including a horizontally disposed cutter element adapted to make an incision in a mine seam above the incision made by the cutter element of the mining machine, an upright shearing cutter element adapted to make an upright incision in the seam between the inner ends of the said first and second mentioned incisions, means for loading the mined material on to the face conveyor, haulage means for imparting feeding movement to the mining machine and the attachment, means for removing cuttings from the cutter element of the mining machine, a driving motor, and speed-reducing gearing for transmitting power from said motor to the said second and third mentioned cutter elements and to said loading, haulage and removing means.

2. An attachment as claimed in claim 1, including a gear-casing surmounted by a rotatable turret carrying a cutter jib, and an adjoining casing housing the motor.

W. A. LOGAN.
